CARL S. HANAU, OF NEW YORK, N. Y.; DOROTHY G. HANAU EXECUTRIX OF CARL S. HANAU, DECEASED.

PAPER-FEEDING MACHINE.

1,376,875.

Specification of Letters Patent.

Patented May 3, 1921.

Application filed May 18, 1918, Serial No. 235,412. Renewed September 7, 1920. Serial No. 408,774.

To all whom it may concern:

Be it known that I, CARL S. HANAU, a subject of the King of the United Kingdom of Great Britain, and a resident of the city 5 of New York, in the county of Bronx and State of New York, have invented certain new and useful Improvements in Paper-Feeding Machines, of which the following is a specification.

10 The present invention relates to paper feeding machines, for printing presses, ruling machines, and the like, for feeding in regular order of succession sheets from a pile or stack of paper, which is suitably 15 arranged on a table located in proximity of the apparatus. The invention pertains more particularly to combination pneumatic and friction separators.

19 In certain types of paper feeding machines, the separating and feeding means serves at the same time to "comb" the sheets or, in other words, to slightly project a few sheets on top of the pile, prior to 25 their engagement by the separators. In other types, again, special combing means are made use of. In both of these types serious difficulties have been experienced, due to the fact that the combing operation in time advances the top sheets of the pile 30 in a manner that they are engaged by the conveying means without being first separated. Moreover, the combing operation often has a tendency to so position the sheets that their lateral edges extend under a slight 35 angle to the line of travel thereof, with the result that the separator causes the top sheet to be forwarded to the conveying means in the wrong position.

40 The main object of the present invention is to provide a device that overcomes these defects by causing the combing means to so position the sheets that their lateral edges are parallel and their front edges perpendicular to the line of travel.

45 Another object of the invention is to so construct the machine that the combing operation brings the top sheet of the pile to a predetermined position, at which position the separating means becomes operative, thereby preventing sheets from being carried to the conveying means without the aid of the separating mechanism.

50 A further object of the invention is to generally improve and simplify the feeding machines.

With these and other objects in view, which will more fully appear as the nature of the invention is better understood, the same consists in the combination, arrangement and construction of parts hereinafter 60 described, pointed out in the appended claims and illustrated in the accompanying drawings, it being understood that many changes may be made in the size and proportion of the several parts and details of 65 construction within the scope of the appended claims without departing from the spirit or sacrificing any of the advantages of the invention.

Two of the many possible embodiments of 70 the invention are illustrated in the accompanying drawings, in which:—

Figure 1 is a side elevation, partly in section, of a paper feeding machine constructed in accordance with the present invention; 75 Fig. 2 is a front elevation of a portion thereof, also partly in section; Fig. 3 is a section taken on line 3—3 of Fig. 1; Fig. 4 is a side elevation of part of the mechanism shown in Fig. 2; Fig. 5 is a top plan view, on 80 a larger scale, of the combing means of the machine; Fig. 6 is a section taken on line 6—6 of Fig. 5; Fig. 7 is a front elevation of the pneumatic separator; Fig. 8 is a bottom plan view thereof; Fig. 9 is a section taken on line 9—9 of Fig. 7; Fig. 10 is a side elevation of a modified pneumatic separator; Fig. 11 is a front elevation thereof; Fig. 12 is a bottom plan view of the same; and Fig. 13 is a side elevation, partly 85 in section, of a modification of the separating means of the machine.

Referring now first to Figs. 1 to 8, inclusive, the numeral 20 indicates one of the side frame members of the machine, of 90 which there are two, one on each side of the machine, said frame members being connected in any suitable manner, for instance by tie-rods 21 and 21'. The stack of paper, denoted by the numeral 22, is supported by 100 a table 23, which is automatically raised, for bringing the top sheet into position for separating, by means herein not referred to, as the same does not form part of the present invention. The stack of paper is 105 guided in its upward movement by a transverse frame 24, having at its upper end a forwardly bent inclined lip 25, provided at its free end with an upwardly projecting ledge 26. In front of this ledge are mount- 110

ed, in a manner presently to be described, shelves 27, which constitute, as will herein-after appear, the lower and stationary mem-bers of the separating device. These shelves 5 are pivoted at 28 to brackets 29, the latter being attached in any suitable manner to the transverse frame 24, their upper faces being provided with friction strips, preferably made of rubber. The rear edges of the 10 friction strips are disposed substantially flush with the ledge 26, their front edges being somewhat higher. The shelves 27 are yieldingly held in such inclined positions by springs 27'.

15 The main shaft 30 of the machine is journaled in the side frames 20, and is ro-tated from any suitable source of power, for instance from the cylinder shaft by the inter-mediate of a chain 31, meshing with a 20 sprocket wheel 32 on the said main shaft. This shaft operates, by a suitable inter-mediate mechanism, the feeding and separating means of the apparatus. The feeding and separating means is attached, in a manner 25 hereinafter to be described to a rock-shaft 33, the reduced ends 34 of which are slid-ably arranged in horizontally extending slots 35 in the side frame members 20. To this rock-shaft is fixedly attached, near one 30 of its ends, a crank 36, the pin 37 of which is slidably arranged in a horizontal guide 38, which, in turn, is slideable in a vertical slot 39 in one of the side frame members. A spring 40, attached to one of the side 35 frame members and to the said guide, serves to keep the latter in its lowermost position. Links 41 connect the rock shaft 33 with levers 42, the latter being fixedly attached to a rock-shaft 43, journaled in the side frame 40 members. To the last-named rock-shaft is rigidly secured a lever 44, carrying on its free end an anti-friction roller 45, seated in the groove 46' of a cam 46. This cam is fixedly attached to the main shaft 30. The 45 guide 38 is engaged by a bell-crank lever 47, that is fulcrumed at 47' to the side frame members and co-operates with a cam 48 upon the main shaft 30. The construction of the cam 48 and the relation thereof to the cam 46 will be described, in detail, hereinafter.

50 On the rock-shaft 33 is mounted the sheet advancing and separating means. This means comprises a suitable number of rollers 49, each attached to a spindle 50, which is 55 rotatably journaled in a forked lever 51. These levers are fixed each to a spindle 52, the latter being oscillatably mounted in cranks 53 on the rock-shaft 33. The rollers 49 are each provided with a friction cover-ing, preferably of rubber, or any other suit-able material, the coefficient of friction of 60 which is greater than that of paper upon paper. Fixedly attached to each spindle 50 is a ratchet wheel 54, adapted to be engaged 65 by a tooth 55' of a hook 55, that is pivoted

at 56 to the respective lever 51. The front end 57 of each hook projects a considerable distance in front of the respective roller 49, for a purpose hereinafter to be described. On each crank 53 is formed a stop 58, which 70 limits the downward motion of the respec-tive lever 51, a spring 59 tending to force the said lever against the said stop. With each roller 49 co-operates a suction device 60, comprising a casing 61, having a flat per-forated underface 62, that is adapted to rest upon the top sheet of the pile of paper, said casing being pivoted at 63 to a lever 64, the latter being fixed to the spindle 52 of the re-spective lever 51. A spring 65 and a stop, 75 similar to the stop 58 above mentioned, co-operates with each lever 64. Each casing 61 communicates through a, preferably, flexi-ble hose 66 with a pipe 67, that extends across the feeding machine. This pipe is 80 provided with a valve casing 68, inter-mediate a suction device (not shown) and the flexible hose 66. In this casing is disposed a valve 69, the stem 70 of which is provided with a fork-shaped head 71, carrying an 85 anti-friction roller 72. This roller coacts with a cam 73, mounted upon the main shaft 30. The head 71 is slidably arranged be-tween guides 74 on one of the side frames 90 of the machine, said guides being parallel to the longitudinal axis of the valve stem. A spring 75, wound upon the valve stem 70, serves to keep the anti-friction roller 72 continuously in engagement with the cam 73.

95 Each shelf 27 is mounted in the path of a roller 49 and a casing 61, co-operating therewith. On the side of each shelf, im-mediately in front of the ledge 26, is mounted an upwardly projecting brush 76, which has a tendency to keep back the paper 100 sheet or sheets below the top sheet, in case the suction device lifts, in a manner herein-after to be described, more than one sheet 105 of paper.

110 The top sheet of the pile of paper is ad-vanced by the feeding and separating means above described within the reach of conveying means, consisting of a roller 77, which is rotated by means of a chain 78 from any suitable source of power. Pres-115 sure rollers 79 coact with the roller 77. Each of these pressure rollers is mounted upon one arm of a bell-crank lever 80, said levers being fulcrumed to the tie-rod 21', and carrying each on their free ends a roller 120 81, co-operating with cams 82, on the main shaft of the machine. The purpose of the cams 82 is to lower the pressure rollers at times when the front edge of a top sheet 125 of the stack of paper reaches the roller 77.

To the rock shaft 33 is loosely attached a rearwardly extending arm 83, that is pro-vided at its rear end with pins 84, engag-ing vertical slots 85 in a frame 86. To this frame is fastened a horizontal spindle 87, on 130

which are rotatably mounted rollers 88, adapted to engage the stack of paper at its rear edge. In order to keep the frame 86 in vertical position, there are mounted thereon, 5 in front of the rollers 88, small rollers 89. The ends of the spindle 87 project beyond the rollers 88, and are seated in grooves 90 in horizontally extending frame members 91. Each of grooves 90 is practically U-shaped, as clearly appears in detail from Fig. 6 of the drawings, guiding the movement of the frame 86, in a manner hereinafter to be described. The frame members 91 are pivoted at 92 to a transverse 10 horizontal bar 93, that is adjustably mounted upon stationary frame members 94, the latter being secured to posts 95, supporting the table 23. To the transverse bar 93 are attached forwardly and downwardly extending springs 96, which are of different lengths, adapted to rest on the rear edges of a few of the top sheets of the stack of paper, whereby the sheets lying underneath the top sheet are prevented from movement, 15 20 as the top sheet is carried forward. The frame members 91 are held in their normal horizontal positions by springs 97, which bear against the tie-rod 21. To the said tie-rod is attached a leaf-spring 98, carrying 25 upon its free end a roller 99. This roller is adapted to rest on the top sheet. With the spring 98 coöperates a lug 100, carried by the arm 83. The spring is mounted in the path of the said lug, so that, as the arm 30 35 40 45 50 55 60 65 70 75 80 85 90 95 100 105 110 115 120 125 130 83 moves forward, that is to say toward the pressure roller 77, the said lug will lift the spring 98 and thereby disengage the roller 99 from the top sheet of the pile of paper.

The operation of this device is as follows:—A few sheets on top of the pile are moved by the combing rollers 88, the operation of which will be described hereinafter, and also by the rollers 49 onto the inclined 40 45 50 55 60 65 70 75 80 85 90 95 100 105 110 115 120 125 130 lip 25 of the transverse frame 24. The top sheet is stopped in its forward movement, as the sheets are being combed, by the ledge 26 on the lip 25, its forward edge being held at right angles to the line of travel of the separating means.

When the rock-shaft 33 is in its outermost position to the right, the horizontal guide 38 is in its lowermost position, in which both the rollers 49 and the suction casings 61 rest 55 on the top sheet of the stack. The hooks 55 also rest on the top sheet, whereby their teeth 55' are disengaged from the ratchet wheels 54. As the rock-shaft now starts forward, that is to say to the left, the rollers 60 65 70 75 80 85 90 95 100 105 110 115 120 125 130 49 are allowed to rotate freely, and do therefore not move the top sheet, except that they aid in the combing operation. When, in the further forward movement of the rock-shaft, the front edge of the suction casings 61 reach the ledge 26 of the forwardly

bent lip 25, the hooks 55 are disengaged from the top sheet, whereby the teeth 55' engage the teeth of the ratchet wheels 54, with the result that the rotation of the rollers 49 is stopped, as they move farther toward the 70 roller 77. As soon as the forward edges of the suction casings 61 reach the ledge 26, the cam 48 causes, by the intermediary of the bell-crank lever 47, the horizontal guide 38 to be slightly raised, thereby giving the 75 rock-shaft a slight turn. Due to this turn both the suction casings and the friction rollers 49 are slightly raised. Before this raising operation, the cam 73 causes the valve 69 in the casing 68 to be unseated, 80 whereby a vacuum is created in the suction casings, the result being that, as the said suction casings and rollers 49 are raised, the top sheet is elevated slightly above the plane of the ledge 26. The vacuum is maintained 85 then during the remainder of the forward stroke of the suction casings, which carry thus the top sheet within the reach of the conveying means. Both the suction casings and the rollers 49 coöperate with the friction strips on the shelves 27, the rollers 49, by reason of their rotation being stopped, separating the sheets, if by accident, more than one sheet has been carried forward. The sheets, lying underneath the top sheet, 90 95 100 105 110 115 120 125 130 are prevented from movement by the brushes 76, on the sides of the said shelves. The rollers 49 act thus, in conjunction with the shelves, both as separating and advancing means; the main purpose of the suction casings being to elevate the top sheet above the ledge 26. These suction casings serve also an additional purpose, towit: They maintain the front edge of the sheet being advanced perpendicular to the line of travel of the friction rollers 49, so that, in case one of these rollers works improperly, the sheet will not be wrongly placed between the conveying means. The ledge 26 has the function of gage for the front edge of the top sheet, as appears from above, and prevents also the sheets on top of the pile from being combed too fast and thus advanced to the conveying means without separation.

When the suction casings 61 and the rollers 49 have reached their foremost positions, the top sheet is within the reach of the conveying roller 77, at which time the pressure rollers 79 are moved downward, whereby the sheet is conveyed to the printing press. 120 As soon as the conveying roller 77 engages the sheet, the cam 73 permits the valve 69 to be seated so that the suction casings release the sheet of paper. After this the horizontal guide 38 is raised, rocking the 125 shaft 33, and thus elevating the suction casings and rollers 49, that is to say disengaging the same from the sheet. These elements are kept in raised positions until the rock-shaft reaches its rear position, when 130

the said casings and rollers are again moved into contact with the stack of paper.

From the foregoing it appears that the rollers 49 and casings 61 are caused to become operative at a predetermined point from the front edge of the paper sheet and also at the same points in their travel toward the ledges 26.

The springs 96 prevent the sheets below the top sheet from moving with the top sheet, inasmuch as they engage a number of sheets below the top sheet.

The rollers 49, obviously, act as combing means in coöperation with the rollers 88 in front of the springs 96. The rollers 88 engage, when the rollers 49 are in their rear positions, the sheets below the top sheet and move forward with the rollers 49, thus combing out the sheets below the top sheet.

20 As soon as the spindle 87 of the rollers 88 reaches the lower legs of the substantially U-shaped grooves 90, the said rollers are lifted off the stack of paper and are held in such positions during part of the forward stroke of the rollers 49 and during their entire rearward stroke. When reaching the end of the rearward stroke, the rollers 88 drop by gravity onto the rear edges of the sheets below the top sheet. In each

25 U-shaped groove 90 is disposed a spring 101, which is forced upward as the lugs 87 move forward, serving then as a support for the said lugs during part of the rearward travel of the rollers 88. To aid in the 30 combing operation, the spring-pressed roller 99 must rest on the top sheet. As the top sheet is, however, being forwarded, the said roller must be raised. This is accomplished by the lug 100, raising the spring 98 at the 35 proper point in the forward travel of the arm 83.

With certain kinds of paper it is sufficient to employ the friction rollers 49 alone for the combing operation. When this is 45 the case, the arm 83 is disengaged from the frame 86, and the latter, with the frames 86, swung around the pivots 92 in the direction of the arrow shown in Fig. 2 of the drawings adjacent the same, thereby bringing 50 the same into inoperative position.

In some cases it may be found advisable to do away entirely with the friction rollers 49. In such a case a suction casing 61 is employed, having a spring-pressed shoe 55 110 pivoted at 111 to the rear portion thereof (Figs. 10 to 12, inclusive). This shoe is covered at its lower surface with a friction strip 112, taking thus the place of the rollers 49.

60 The suction casings 61, shown in detail in Figs. 7 to 9, inclusive, may be provided on their sides and rear end with a friction body 113, having a function similar to the shoe 110 mentioned.

65 Instead of employing the brushes 76 for

the purpose mentioned, a roller 114 may be mounted in front of the inclined lip 25 (Fig. 13). This roller is provided with a friction covering 115, and is rotated continuously by any suitable means in the direction of the arrow shown in Fig. 13 adjacent the same. This roller aids in the separation of the sheets, having a tendency to keep back the sheet below the top one by rotating in a direction opposite to the direction of travel of the top sheet. Instead of a friction covering, a brush surface may be attached to the roller.

What I claim is:—

1. In a machine for feeding sheets of paper from a stack, the combination with a pneumatically acting reciprocating separating member, of means for causing said member to become operative at a predetermined point in its travel and at a substantial distance from the beginning of its forward stroke, and means for raising said member as soon as operative, thereby lifting the top sheet of the stack. 80

2. In a machine for feeding sheets of paper from a stack, the combination with a pneumatically acting reciprocating separating member, of means for causing said member to become operative at a predetermined point from the beginning of its forward stroke and at a predetermined point from the front edge of the top sheet of the stack, and means for raising said member as soon as operative, thereby lifting the top sheet of the stack. 90

3. In a machine for feeding sheets of paper from a stack, the combination with a pneumatically acting reciprocating separating member, of a stationary separating member coöperating therewith and being normally disposed above the top sheet of the stack, means for causing said reciprocating member to become operative at a predetermined point in its travel and at a substantial distance from the beginning of its forward stroke, and means for raising said reciprocating member as soon as operative, thereby elevating the top sheet of the stack onto said stationary separating member. 105

4. In a machine for feeding sheets of paper from a stack, the combination with a pneumatically acting reciprocating separating member, of a stationary separating member coöperating therewith and being normally disposed above the top sheet of the stack, means for causing said reciprocating member to become operative at a predetermined point from the beginning of its forward stroke and at a predetermined point from the front edge of the top sheet of the stack, and means for raising said reciprocating member as soon as operative, thereby elevating the top sheet of the stack onto said stationary separating member. 110

5. In a machine for feeding sheets of 120

paper from a stack, the combination with a frame having an inclined lip in front of the stack of paper, said lip having along its front edge an upwardly projecting ledge 5 serving as a stop for the top sheet of the stack, a stationary separating member in front of said ledge and projecting above the same, a pneumatically acting reciprocating separating member coöperating with said stationary separating member, means for causing said reciprocating member to become operative when reaching said ledge, and means for raising said reciprocating member as soon as operative, thereby elevating the top sheet of the stack onto said stationary separating member.

6. A machine for feeding sheets of paper from a stack, comprising a feeding roller having a bodily motion to and from the front edges of the sheets and adapted to engage the sheet to be fed, means for causing the front edges of a few of the sheets on top of the stack to protrude in front of the front edge of the stack, and means for arresting the rotation of said roller at a predetermined point from the front edge of the top sheet, the combination of means for causing the arresting point to coincide with a predetermined point in the travel of said roller.

7. A machine for feeding sheets of paper from a stack, comprising a feeding roller having a bodily motion to and from the front edge of the sheet and adapted to engage the sheet to be fed, and means for arresting the rotation of said roller at a predetermined point from the front edge of said sheet, the combination of a ledge in the path of said roller serving as a stop for the sheet and thereby determining the point in the travel of said roller at which the said arresting means become operative.

8. A machine for feeding sheets of paper

from a stack, comprising a feeding roller having a bodily motion to and from the front edges of the sheets and adapted to engage the sheet to be fed, means for causing the front edges of a few of the sheets on top of the stack to protrude in front of the front edge of the stack, and means for automatically arresting the rotation of said roller at a predetermined point from the front edge of the top sheet, the combination of means for causing the arresting point to coincide with a predetermined point in the travel of said roller.

9. A machine for feeding sheets of paper from a stack, comprising a feeding roller having a bodily motion to and from the front edge of the sheet and adapted to engage the sheet to be fed, and means for automatically arresting the rotation of said roller at a predetermined point from the front edge of said sheet, the combination of a ledge in the path of said roller serving as a stop for the sheet and thereby determining the point in the travel of said roller at which the said arresting means become operative.

10. In a machine for feeding sheets of paper from a stack, the combination with a pneumatically acting reciprocating separating member for advancing the top sheet of the stack, of frictional means in the path of said reciprocating member for controlling the separation of the top sheet of the stack of paper, said frictional means being disposed higher than the top sheet in its normal position, and means for raising said pneumatically acting reciprocating member, when operative, thereby lifting the top sheet of the stack onto said frictional means.

Signed at New York, in the county of New York and State of New York, this 2nd day of May, A. D. 1918.

CARL S. HANAU.
